UNITED STATES PATENT OFFICE

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA

COKING RETORT OVEN

Application filed December 28, 1926. Serial No. 157,556.

This invention comprehends improvements of general utility in coking retort oven art; and also comprehends certain improvements especially applicable to coking retort ovens of the well known cross-regenerative type exemplified in the patent to J. Becker, No. 1,374,546, dated April 12, 1921.

The invention has for its objects the provision of a coking retort oven having, as an important characteristic, an extreme flexibility in operation and the ready adaptability of the oven for operation either with producer gas as a fuel, or with coke-oven gas burned in an atmosphere of ordinary pre-heated air, such as is utilized in ordinary coke ovens, or with coke oven gas burned in an atmosphere containing both air and a neutral gaseous diluent which is introduced into the combustion flues separately from the air. By the invention, a quick and ready conversion of the oven for operation according to any one of the modes specified, may be effected without making any material adjustments, other than varying the operation of installed control parts, as will be herein-after more fully explained.

A further object of the invention is to provide control mechanism for periodically reversing the operation of a single group of regenerators and their heating flues, such group being disposed into in-flow and out-flow regenerators and flues, one group at a time throughout a coke oven battery and the reversal of the flow through regenerators and flues for individual ovens in succession, i. e., one oven after the other, instead of reversing the flow for a battery of ovens at one pull of the reversing mechanism. By maintaining in continuous motion the mechanism that operates the levers that reverse the valves for the gas supply, air supply, and waste gas outlets, a great saving in energy is effected by reason of the fact that the amount of energy consumed in maintaining such mechanism in continuous motion is less than the initial energy consumed in stopping and restarting such mechanism when it is operated intermittently. By the invention, two such continuously moving mechanisms are used each having a dog for moving engagers, in-

dividual to each group of regenerators and flues, that actuate said valves. These continuously moving mechanisms are timed so that approximately one hour is consumed before each dog passes a given point and, therefore, each dog actuates each engager once every hour. The dogs are located on each of said mechanisms so that they are spaced approximately one-half hour apart from each other, thereby providing a periodic reversal of flow through the regenerators and flues for individual ovens every one-half hour; and both continuously moving mechanisms actuate the valves for only one single group at a time and actuates the valves for the groups, one group after the other in succession, thereby avoiding the necessity of requiring sufficient energy to reverse the valves of a great many ovens at one instant every half hour, by an intermittently operating mechanism.

In addition to the general objects recited above, the invention has for further objects such other improvements or advantages in construction and operation as are found to obtain in the structure and devices herein-after described or claimed.

In the accompanying drawings, forming a part of this specification, and showing, for purposes of exemplification a preferred form and manner in which the invention may be embodied and practiced, but without limiting the claimed invention specifically to such illustrative instance or instances:

the reversing mechanisms on the coke side of the oven battery.

Fig. 5 is a diagrammatic horizontal sectional view taken through a coke oven battery, showing the reversing mechanism in plan view.

Fig. 6 is a view similar to Fig. 4 but illustrating the continuously moving chain mechanism which actuates the reversing mechanism on the pusher side of the oven battery.

Fig. 7 is a composite vertical sectional elevation taken transversely of a coke oven battery in planes indicated by the lines D—D, E—E and F—F of Fig. 1.

Fig. 8 is a composite vertical sectional elevational view taken transversely of a coke oven battery in planes indicated by the lines B—B and C—C of Fig. 2.

The same characters of reference indicate the same parts throughout the several views.

In the embodiment of the invention illustrated in the drawings, the invention is incorporated in a combination coke oven battery, i. e., a battery having provision for being operated either with producer gas as a fuel or with coke oven gas burned in an atmosphere of ordinary preheated air, such as is utilized in ordinary coke ovens, or with coke oven gas burned in an atmosphere containing both air and a neutral gaseous diluent which is introduced into the flame flues separately from the air. A combination coke oven battery having these features is shown and described in patent to J. Becker, No. 1,374,546, dated April 12, 1921.

For convenience, the present description will be confined to the present illustrated embodiment of the invention in such combination oven battery; the novel features and improvements made by the invention are susceptible of other applications, such, for example, as for ordinary so-called "coke ovens" employing coke oven gas as a fuel, or for ordinary so-called "gas ovens" employing producer gas as a fuel; hence, the scope of the invention is not confined to the specific use and specific embodiment herein described as an illustrative example.

Referring to the drawings, there are illustrated views of a coke oven battery or plant of the by-product type, having features above specified; said oven battery embodies in its construction a plurality of crosswise elongated heating walls 11 and a plurality of intermediate crosswise elongated coking chambers 12. The heating walls 11 form the side walls of the respective coking chambers 12, as shown more particularly in Fig. 1, and, in the present instance, are directly supported by the heavy supporting or pillar walls 13 and 22, Figs. 1, 5 and 7, which extend crosswise of the battery. These pillar walls, together with other walls, hereinafter described, collectively form the main support for the entire super-structure of the oven

battery and are themselves supported upon a flat mat or platform which constitutes the sub-foundation on which the entire battery rests.

The coal to be coked is charged into the several coking chambers or ovens through charging holes 14 located in the top 15 of the oven battery and positioned directly above the oven or chambers 12, as shown in Fig. 1. These charging holes 14 are equipped with the usual removable covers, which are removed during the charging of the individual ovens or coking chambers and which are placed in position to close the tops of such coking chambers during the coking or distilling operation. The gases of distillation pass from the tops of the several coking chambers 12 through gas outlets 16 (Fig. 1) and thence through ascension pipes (not shown) into the usual gas collecting main which carries the distillation products to the by-product recovery apparatus.

Heat for coking the charges of coal in the several ovens or chambers 12 is derived from the heating walls 11, which, as above mentioned, extend crosswise of the battery at the sides of the coking chambers. Each heating wall 11 is constituted of a plurality of the usual flame or combustion flues 17 and are operatively disposed in a single group, that is to say all of the flues of each heating wall operate concurrently as upflow or downflow flues, as will be hereinafter more fully explained. When the flame flues on one side of a coking chamber are burning, that is to say, operating for upflow, the flame flues on the opposite side of the same coking chamber are operating for downflow to permit exhaust of the waste gases. Consequently flame heating is maintained continuously from end to end on one side of a charge of coking coal in each coking chamber, the flame heat being applied to the full length of one side of such charge during an entire period, and, then, after reversal, being applied to the full length of the opposite side of the charge, until a subsequent reversal is effected.

The crosswise regenerators 18 of the retort oven or battery are located in planes beneath the planes of the aforesaid heating walls 11 and coking chambers 12, and, in the present instance, extend in parallelism between the pillar walls 13, and the other heavy supporting walls 22, hereinafter described. Located in the middle lengthwise vertical plane of the coke oven battery, is a vertical partition 19, as shown in Fig. 1, which partition extends all the way up from the mat of the battery to the bottom of the overlying coking chamber and from one to the other of the pillar walls 13, and the other walls 22 which are between the pillar walls. The regenerators, which are respectively located on opposite sides of the battery, extend inwardly to

said partition 19 and are separated thereby. This arrangement permits control from opposite sides of the battery of the flow through the regenerators, thereby assisting the flue arrangement in promoting uniformity of distribution.

Each regenerator 18 is a chamber containing open brick work, commonly called checker work, and indicated at 20, with a distributing sole channel 21 underneath such checker work, the channels forming the soles of such chambers and opening up into the checker work. A heavy vertical gas-tight supporting wall 22 extends directly beneath each of the coking chambers in parallelism between each two adjacent pillar walls 13 (Fig. 5) and such supporting walls 22 provide two regenerators G and H located respectively on the opposite sides of such walls 22 and between adjacent pillar walls 13. The several walls 22 also have the function with the pillar walls 13 of supporting the weight of the battery super-structure.

This supporting wall construction provides two series of cross-wise-extending parallel gas-tight load-carrying walls located below the coking chambers and intermediate heating walls, the pillar walls 13 of one series being directly beneath the heating walls and the supporting walls 22 of the other series being directly beneath the coking chambers. The walls 22 which are beneath the coking chambers are constructed and function not as mere partitions commonly employed, but as true load-carrying gas-tight walls, permitting relatively different pressures to be maintained in the checkerwork chambers on the opposite sides of such walls, or the flow of different media in the checkerwork chambers separated by these walls, without leakage from one checkerwork chamber into another and without danger of mixing gases in the checkerwork chambers which must be kept separate in this region of the battery.

The regenerators G and H are heated, in alternation, by the hot combustion products that draw off from the flame or combustion flues hereinbefore mentioned and then impart such heat to the medium that they feed into these flame flues; in the present instance, the flow through the regenerators, G, H, between each two adjacent pillar walls 13 is maintained concurrently in opposite directions, for example, when the flow is passing up through a regenerator G on one side of supporting wall 22, down-flow is being maintained concurrently through the other regenerator H on the other side of that supporting wall 22.

Each of the cooperating regenerators G and H is provided with a series of ducts 23, each duct of each series leading respectively to one of the individual flame flues of the heating wall which is supported by the wall 13 between said regenerators. With this construc-

tion, each flame flue communicates by a plurality of ducts 23 with adjacent separate regenerators G and H and the flow through the regenerators which are respectively located on opposite sides of a pillar wall 13, is maintained concurrently in the same direction, that is to say, both of said regenerators are either operating for inflow or for outflow.

In the present embodiment of the invention, the entire series of flame flues of each heating wall 11 is either burning or operating for down-flow to convey waste gas products to the regenerators beneath and consequently the regenerators aligned on opposite sides of the central longitudinal partition 19 operate concurrently for flow in the same direction and in the same manner. The reversal in flow through the flame flues on opposite sides of a coking chamber, and their communicably connected regenerators may thus be said to take place longitudinally of the oven battery, instead of transversely thereof. The reversal of the oven is effected at the end of an operating period which is determined by practice, and by means of the novel reversing mechanism presently to be described. The function of such reversal is as follows: The regenerators that prior to the reversal operated as inflow regenerators become outflow regenerators, and the outflow operating regenerators become inflow operating regenerators; the up-burning series of flue switches function with the down-burning series of flues of the next adjacent heating wall, and the supply of gas is turned off from the previously up-burning flues and turned on into the mains of the previously down-burning flues, as is fully shown and described in the patent to J. Becker, No. 1,374,546, previously mentioned.

Each flame flue of each heating wall has at its top a port or opening 24 for draft and the passage of combustion products or waste gas from the flame within the flue. These ports open up into horizontal transversely extending bus flues 25' formed in the heating walls and connecting all of the vertical flues that communicate therewith through said ports. Each heating wall is provided with a plurality of, in the present instance, two of such horizontal flues which are positioned end to end with respect to each other and respectively located on opposite sides of the plane of the wall 19 as indicated by the central dividing line L in Fig. 1.

The two horizontal flues of each heating wall are communicably connected, by means of passageways 25, with the corresponding horizontal flues of one of the next adjacent heating walls. That is to say the horizontal flues 25' of the up-burning flues on one side of an oven is communicably connected with the down-burning flues on the other side of the same oven by means of the said passageways. These passageways or channels 25 pre-

erably open up into substantially the middle portions of their respective connected flues, as shown in Fig. 1, and extend in a direction longitudinally of the oven battery. Thus the 5 entire flow from a heating wall, within the flues of which combustion is being maintained, passes through said passageways and downwardly through all of the flues of the next adjacent heating wall and each reversal 10 operation is accompanied by a reversal in the direction in the flow of all of the flues of each heating wall.

The draft through the ports may be regulated by means of the usual movable dampers or sliding bricks, positioned in the ordinary way in the bottoms of the horizontal flues 25' and adapted to be reached by access flues 28 which extend from the top of the horizontal flues in each heating wall to the 20 top 15 of the battery, there being an access flue positioned over each flame or combustion flue of each heating wall.

Extending crosswise of the battery in each pillar wall 13 and located in end to end relation with respect to each other beneath the heating wall 11 thereabove are two gas supply channels 26. These channels are for the purpose of supplying coke oven gas to the several flame flues on each side of the central 25 line L, and to accomplish this end, the channel on the near or pusher side of the battery communicates with the individual flues on the same side of the said line L by means of ducts that lead from such channel individually into the bottoms of individual flues; and the channel which supplies the several flues that are located on the far or coke side of the battery communicates therewith by means of similarly connecting ducts 31. Within the 30 several ducts are disposed the usual nozzles 32 which direct the flame vertically within the heating or flame flues.

The hereinbefore described structure is shown and described in detail in the patents 45 to J. Becker, Nos. 1,374,546 and 1,416,322 and the present invention relates to the reversing mechanism for the battery, the parts that are not needed for an understanding of this invention having been omitted from 50 the drawings.

As previously stated, the sole channels 21 extend in opposite directions beneath the checker work of the respective regenerators on opposite sides of the vertical partition 19 55 and each of these channels is provided with a flow box 33. The flow boxes 33 are arranged in pairs along each side of the oven battery and communicate with waste gas tunnels 34 through vertical ducts 35.

60 The flow boxes 33 which communicate with the regenerators G and H are indicated at g and h respectively in Fig. 2 of the drawings. By this arrangement the flow boxes g and h of each pair communicate through their respective regenerator G and H with a single

heating wall. Gas mains 36 are mounted upon bracket members 37 and extend longitudinally along opposite sides of the battery. These mains are communicably connected to sources of supply of both coke oven gas and 70 a special generator gas, such as producer gas, and when the oven is being operated with either of these gases as a fuel, the mains 36 are cut off from the supply of the other gas. That is to say, the mains 36 are employed to separately supply either coke oven gas or producer gas to the flame flues, according to the desired operation of the battery. 75

A plurality of vertically extending pipes 80 38 are arranged along each side of the battery and are communicably connected at their upper ends with the gas mains 36 by means of horizontally disposed pipes 39 and are similarly connected, adjacent to their lower ends, 85 with the flow boxes h of each of the pairs of flow boxes by means of pipes 40 and valve members 41. These pipes 38 are also connected with the ducts and flame nozzles of the gas supply channels 26, which are located 90 in the lower portion of the several flame flues, by means of upwardly and inwardly inclined pipes 42, vertically disposed pipes 43, and horizontally positioned pipes 44. A valve 45 provided with an operating lever 46 is located in each of the vertical pipes 43 by means of which the supply of gas to the nozzles in the gas mains 26 may be interrupted when the oven is operating with producer gas as 95 a fuel, as will be hereinafter described. 100

Valve members 47, provided with operating levers or arms 48, are located in the vertical pipes 38 and are adapted to be periodically actuated in alternation to establish and disestablish communication between the gas mains 36 and the regenerators and flame flues of the oven. The flow boxes g and h of each of the pairs of regenerators are each respectively provided with internally disposed exhaust valves or dampers 50 and 51, 110 as indicated by dotted lines in Fig. 2. The valve members 50 and 51 of each pair are provided with operating levers 52 and 53 which are connected together at their upper ends by means of links 54 so that the valves 50 and 51 of each of the pairs of flow boxes will move in unison to simultaneously establish or interrupt communication between their respective sole channels 21 and the waste gas tunnels 34. 115

The flow boxes "g" and "h" of each pair are also respectively provided with air inlet valve members or covers 55 and 56 which may be periodically opened to admit air to the flow boxes under certain conditions of operation, as will be presently described. The valve members 55 and 56 are respectively pivotally connected to the arms 57 and 58 of bell crank levers 59 and 60 which are mounted upon the upper portions of the flow boxes g 130

and h as at 61. The other arms 62 and 63 of the bell crank levers 59 and 60 extend upwardly and may be connected similarly to the flow box valve levers 52 and 53 in pairs by means of links 64, which are shown in dotted lines in Fig. 2. However, in the particular operation to be described the covers 56 of the flow boxes h are not operated but are maintained in closed positions throughout the operation of the oven battery and are employed only in connection with a fuel gas which requires a larger percentage of air for satisfactory combustion. The covers 55 of the flow boxes g are actuated under all conditions of operation, and are moved simultaneously with the exhaust valves or dampers 50 and 51 of the adjacent pairs of flow boxes by means of links 65 which cross-connect the arms 62 of the bell crank levers 59, which 15 actuate the air inlet cover 55 of the flow boxes g of one of the pair of flow boxes, with the arms 52 and 53 of the flow boxes g and h of the adjacent pair.

It will be observed from an inspection of Fig. 2 of the drawings that several valve elements of the flow boxes g and h of one of the pairs of flow boxes are mounted to operate in opposite directions from those of the adjacent pair and are so interconnected by means of the above described link and lever mechanism that when the valves 50 and 51 of one of the pairs of flow boxes g and h are open to permit the waste products of combustion to escape to the waste gas tunnels 34, the air inlet valve 55 of the flow box g of the adjacent pair is also in an open position; and conversely, when the valve 55 of the flow box g is in a closed position the valves 50 and 51 of the adjacent pair of flow boxes 40 g and h are also in closed positions. That is to say, the air inlet valve 55 of one pair of flow boxes operates in unison and simultaneously with the exhaust valves 50 and 51 of the adjacent pair. The valve mechanism heretofore described is substantially the same on each side of the battery and the mechanism on each side is actuated in timed relation with respect to each other by means of the following instrumentalities.

55 A frame 66 extends longitudinally along both sides of the oven battery and this frame carries, at spaced intervals, a plurality of transversely extending shafts 67 and 68 which are rotatably mounted in elongated bearing blocks 69. A gear wheel 70 is keyed to the inner extremity of each of the shafts 67 and 68 and each of these gear wheels meshes with and drives a smaller gear wheel 71 that is fixed to the inner extremity of a stub shaft 72. The stub shafts 72 are rotatably mounted in the bearing blocks 69 that support the inner end of each of the shafts 67 and 68 and are each provided with an arm 73 adjacent to their inner ends. A link 74 is pivotally connected at one end to the crank

arm 73 and extends downwardly and is pivotally connected at its other end to the arm 62 of one of the bell crank levers 59 which actuates one of the air inlet valves 55 of the flow boxes g .

70 A gear wheel 75 is keyed at the outer end of each of the shafts 67 and 68 and meshes with a gear wheel 76 which is fixed to the outer end of a stub shaft 77. The shaft 77 is rotatably mounted in one of the bearing blocks 69 carried by the frame 66 and in axial alignment with the stub shaft 72. A crank arm 78 is fixed to the outer end of each of the shafts 77 and is operatively connected to the arm 48 of the gas valve 47 by means of a link 79. The gear wheels 70 and 71 and also the gear wheels 75 and 76 are of a two to one ratio and consequently one quarter revolution of the gear wheels 70 and 75 will cause a one-half revolution of their co-acting gears 71 and 76. The result is that when the gear wheels 70 and 75 are rotated one quarter of a revolution, by means of mechanism presently to be described, the crank arms 73 and 78 will be moved through arcs 90 of 180° to simultaneously either open or close the air inlet valve 55 and gas valve 47 for one pair of regenerators and flues and also the waste gas valves 50 and 51 of the corresponding adjacent pair of regenerators 95 and flues.

100 Each of the shafts 67 is provided with a pair of star wheels or engagers "a" and "b" and the shafts 68 are also each provided with similar engagers "c" and "d". Each of the engagers comprises a hub portion 80 and a plurality of radially extending arms 81 having bifurcated end portions 82. The innermost engagers "a" and "c" of each pair are loosely mounted upon the shafts 67 and 68 for free rotation thereon but the outer engagers "b" and "d" are respectively keyed to the shafts 67 and 68 so that any force tending to rotate the fixed engagers will be transmitted to their supporting shafts. The outer portion of the hub 80 of the loose engager "a" is provided with a sprocket wheel 83 which is connected with a sprocket wheel 84 provided on the inner portion of the hub 80 of the fixed engager "d", that is keyed to the shaft 68, by means of a sprocket chain 85. A sprocket wheel 86 is also keyed to the shaft 67 and is connected with a sprocket wheel 87 which is provided on the hub 80 of the loose engager "c" by means of a sprocket chain 88. 110

115 By means of this particular construction, if the engager "a" is actuated it will rotate freely upon the shaft 67 but will cause the rotation of the fixed engager "d" and the shaft 68, also if the engager "b" is actuated it will cause the rotation of the shaft 67, sprocket wheel 86 and engager "c", through the medium of the sprocket chain 88, but as the engager "c" is mounted loosely upon the shaft 68 no motion will be transmitted there- 120 125 130

to. On the other hand if the loose engager "c" is rotated freely upon the shaft 68 the shaft 67 will be rotated through the medium of the sprocket wheel 87 and the fixed sprocket wheel 86 and the sprocket chain 88 and also cause the rotation of the engager "b" which is keyed to this shaft. If the fixed engager "d" is rotated its shaft 68 will be also rotated together with the engager "a" through the medium of the sprocket chain 85, but as the engager "a" is mounted for free rotation upon the shaft 67 no motion will be imparted thereto.

The several engagers "a", "b", "c", and "d" are actuated periodically and in succession to reverse the operation of the oven battery by means of inner and outer endless engager chains 89 and 90 respectively which extend longitudinally along each side of the oven battery and each of which carries one or more dogs 91 and 92 respectively. The dog 91 carried by the chain 89 is staggered with respect to the dog 92 which is provided on the chain 90 so that the dog 91 will be one-half hour behind the dog 92 and not move the engagers that actuate the valve levers of each oven until one-half hour after the dog 92 moved its respective engagers, and as a consequence the engagers "a", "c", "b" and "d" are alternately actuated.

These chains 89 and 90 pass around a plurality of driving sprocket wheels 93 and 94 which are keyed to a common shaft 95 located at one end of the battery (Fig. 5). At the other end of the battery the chains 89 and 90 pass over idler wheels 96 and 97 which are suitably mounted in a horizontally movable frame structure or carriage 98. A cable 99 passes over a sheave or pulley 100 and is secured at one end to the frame 98 and is provided at its other end with a weight 101 which may be adjusted to maintain the proper tension upon the cables 89 and 90. The upper flights of the engager chains 89 and 90 ride in the bifurcated portions 82 of the engager arms 81 which are therefore constantly in the path of travel of the dogs 91 and 92 but the lower flights of these chains are supported at intervals by means of idler pulleys 102.

A shaft 103 extends transversely across one end of the battery and is provided at each end with a sprocket wheel 104. These sprocket wheels are connected by means of sprocket chains 106 to sprocket wheels 105 which are fixed to the inner ends of the shafts.

One of the shafts 95 is provided with a gear wheel 107 which is driven by an electric motor 108 through the medium of suitable reduction gear mechanism 109. It will be apparent from the foregoing that the hereinbefore described reversing mechanisms located on each side of the oven battery are operated in unison and in timed relation with

each other, and the speed of said chains may be regulated by said reduction gearing so that each of the dogs passes a given point in one hour, or more if desired, depending on the number of dogs on a chain. 70

The operation of the reversing mechanism when producer gas is utilized as a fuel is as follows:

Assuming that the several valves on both sides of the battery are in the positions shown in Figs. 2 and 3 and that the engager chains 89 and 90 are advancing in the direction indicated by the arrow in these figures, the dog 92 has just engaged one of the arms of the outer fixed engager wheel "b", for the four flow boxes from the left hand side of Fig. 2, which are illustrated in the intermediate reversal position, that is, the positions they assume just after a shutoff and before the turn on, and caused the shaft 67 to rotate. This movement of the engager "b" has caused the arm 78 to move one-half of a revolution, and has been previously described, and actuated the valve 47 in the vertical pipe 38 leading to the second flow box from the left hand side, to cut off the supply of producer gas from the flame flues which are supplied through this valve. The arm 73 will also be rotated at the same time one-half of a revolution to move the lever 74 and thereby simultaneously close the air inlet valve 55 of the flow box "g" of the first pair and to close the exhaust valves or dampers 50 and 51 of the flow boxes "g" and "h" of the next adjacent second pair, and the rotation of the shaft 67 will rotate the gear wheel 86 and chain 88 which will rotate the gear wheel 87, but the gear wheel 87 will not cause rotation of the shaft 68 as it is loose thereon and not fixed. The dog 92 will then pass to and engage the arms of the engager "d" which is fixed to the shaft 68 and cause the arm 78 of "d" to move one-half of a revolution, as has been previously described, and actuate the valve 47 through the levers 79 and 48 to turn on the supply of producer gas to the regenerators which are supplied through this valve 47 in the vertical pipe 38 leading to the flow box "h" of the second pair from the left, and the arm 73 of "d" will also be rotated one-half of a revolution and its lever 74 to simultaneously open the air inlet valve 55 of the flow box "g" of the second pair and the exhaust valves or dampers 50 and 51 of the flow boxes "g" and "h" of the first pair. This rotation of the shaft 68 will cause rotation of the engager "a" but the engager "a" will not cause rotation of the shaft 67 as it is loose thereon and not fixed thereto. By the reversal movement just described, the functions of the first pair of regenerators "g", "h", which were operating for inflow will have been reversed and will operate as outflow regenerators when the engager "d" is moved and the second pair of 130

regenerators *g* and *h* which were operating for outflow will then operate for inflow or flame burning.

By reason of the fact that the dogs 91 and 92 are staggered with respect to each other and are disposed at one half an hour's distance apart longitudinally, the dog 91 will next engage the loose engager "a" one half hour after said dog 92 engaged the engager 10 "b" and cause it to rotate one quarter of a revolution. This partial rotation of the engager "a" will not actuate the shaft 67, as it is loosely mounted thereon, but it will cause the simultaneous and corresponding rotation 15 of the fixed engager "d" through the medium of the sprocket wheels 83 and 84 and the sprocket chain 85. This engager, being keyed to the shaft 68 will cause the partial rotation thereof and the arms 73 and 79 20 which are associated therewith to move one half of a revolution and close the exhaust valves 50 and 51 of the first pair of flow boxes *g* and *h* and the air inlet valve 55 of the flow box *g* of the second pair and to also 25 actuate the valve 47 and stop the supply from the gas pipe 38 of the second pair of flow boxes. The dog 91 next passes on and engages the loose engager "c" which rotates the shaft 67 by means of gear wheels 87 and 86 30 and chain 88 and its engagement therewith will cause the gas to flow into the flow box *h* of the first pair and the lid 55 of the flow box *g* of the first pair to open and cause the 35 valves 50 and 51 of the second pair of flow boxes to open and thereby effect a second reversal of flow so that the first pair of regenerators are now operating for inflow and the second pair for outflow.

During the comparatively short period of 40 time between the shutting off of the gas and air in one pair of flow boxes and regenerators and the turning on of the gas and air in the other pair of flow boxes and regenerators, which period is only the time required for the 45 dog 91 to pass from the loose engager "a" to the loose engager "c" or, for the dog 92 to pass from the fixed engager "b" to the fixed engager "d", no gas or air will flow into the 50 flues and the time between the shut off and the turn on is sufficient to allow the gas and air that are still in these flues to complete their combustion before the air and gas is started flowing in the reverse direction.

After the dog 92 passes the engager "d" 55 for the four flow boxes at the left in Fig. 2, it then actuates the engager "b" for the next four flow boxes to the right in Fig. 2 (these 60 four flow boxes together with their valves and levers, etc., illustrate the position of the parts before their reversal) which shuts off the gas and the air on the first two flow boxes and closes the valves 50 and 51 of the next 65 two flow boxes to the right. The dog 92 being in continuous motion then passes on and actuates the engager "d" which turns on the

gas and the air for the second pair and opens the valves 50 and 51 of the first pair, the dog passing on and operating in the same manner each engager "b" and "d" throughout the battery in succession. The dog 91, being one-half hour behind the dog 92, actuates the engagers "a" and "c" for each four flow boxes, one half hour after the dog 92, and it continues on in the same manner, as above described, operating each engager "a" and "c" throughout the battery in succession.

It will be understood that more than one dog may be provided along the engager chains 89 and 90 to actuate each of the engagers but they should be so spaced from each other and the speed of the continuously moving chain regulated so that the flow for each oven is reversed periodically every one-half hour or such other period of time as may be desirable. Each dog 91 engages the engagers "a" and "c" of each oven in succession and each dog 92 engages the engagers "b" and "d" of each oven in succession longitudinally of the battery.

By reason of this timing of the several actuating instrumentalities, producer gas is supplied to the flow boxes *h* of alternate pairs and their communicating regenerators and flame flues and at the same time air is admitted to the regenerators and communicating up-burning flues to support combustion through the cooperating flow boxes *g* of such pairs.

The pairs of flow boxes *g* and *h* which are located between those pairs supplying gas and air to the up-burning flame flues are operating to deliver the waste gas or products of combustion to the waste gas tunnels 34. The operation of the several flame flues consequently progresses longitudinally throughout the length of the battery, the up-burning flues alternately becoming down-burning flues and those operating as down-burning flues alternately becoming up-burning flues.

If it is desired to employ coke oven gas as a fuel the supply of producer gas is cut off from the gas mains 36 and a supply of coke oven gas is turned on into these mains. The arms 62 and 63 of the bell crank levers 59 and 60 which operate the air inlet valves 55 and 56 of the pairs of flow boxes *g* and *h* are connected by means of the links 64 (shown by the dotted lines in Fig. 2) and the arms 48 which operate the gas valves 47 in the vertical pipes 38 are also connected to the arms 46 which operate the valves 45 in the pipes 43, by means of links 110. The valves 41, which are located in the pipes 40, are turned off to prevent the coke oven gas from flowing into the flow boxes *h* which are only used for gas when the oven is operating with producer gas as a fuel.

The operation of the reversing mechanism and valve elements of the oven battery with these slight changes, is substantially the same

as that hereinbefore described in connection with the operation of the oven with producer gas, the only difference being that first, instead of supplying producer gas through the flow boxes "h" that communicate with the up-burning flues, coke oven gas is supplied to these flues through the nozzles located in the pipes 26 in the lower portions thereof; and, second, instead of supplying producer gas through the flow boxes "h", these flow boxes operate in conjunction with the flow boxes "g" of the up-burning flues to supply an increased amount of air through both of the cooperating regenerators G and H, sufficient to produce the proper combustion of the coke oven gas in the up-burning flame flues.

By rearrangement of levers and connections a different sequence of operation of the 20 regenerator and gas valves can be effected, as, for instance, when the gas regenerators are disposed in pairs with each such pair flanked on both sides by air regenerators so located for the purpose of separating the gas regenerators from the counterflow conditions and 25 consequent pressure differential of the next adjacent waste-heat regenerators, the regenerator sequence then being

36 instead of WWWWAPPAWWWWAPPA
WWAPWWAPWWAP
or WWPAAWWPAWWPA

35 and so forth (in which formulae, W is for waste heat and A for air and P for producer gas or other lean gas).

The invention as hereinabove set forth is embodied in a particular form of construction but may be variously embodied within the scope of the claims hereinafter made.

I claim:

1. In a coking retort oven battery in combination: a plurality of retort chambers alternating with heating walls contiguous to such coking chambers and respectively constituted of combustion flues adapted to be subjected to periodical heatings of different intensities; regenerators side by side in a row 45 and disposed in in-flow and out-flow groups and communicably connected with flues, the regenerators for each heating wall being disposed in pairs; flow boxes communicably connected with each regenerator of a pair 50 and with a waste gas outlet, one of said flow boxes and regenerators of a pair being for air and the other of said pair for gas when operating for in-flow and both being for exhaust of waste gas when operating for out-flow, an air valve for each flow box, a waste 55 gas valve for each flow box, means to convey fuel gas optionally communicable with one of a pair of said flow boxes or directly with the flues of each heating wall; a valve in said 60 means to convey fuel gas; a pair of rotatable 65

shafts for each two adjacent pairs of regenerators, each shaft having an engager loosely mounted thereon and each shaft having an engager fixed thereon on the loose engager of the first shaft being operatively connected with the second shaft and the loose engager of the second shaft being operatively connected with the first shaft; a plurality of progressively movable means adapted to actuate said engagers in timed relation, one of said progressively movable means engaging the loosely mounted engagers and the other one engaging the fixedly mounted engagers, said first shaft being operatively connected with the valve in the means to convey fuel gas and with the air valves of one pair of flow boxes for the pair of regenerators for one heating wall and with the waste gas valves of the flow boxes of a next adjacent pair of regenerators for another heating wall, the second shaft being operatively connected with the valve in the means to convey fuel gas and with the air valves for the flow boxes of said next adjacent pair of regenerators for said another heating wall and with the waste gas valves of the flow boxes of the pair of regenerators for said one heating wall. 70 75 80 85 90

2. In a coking retort oven, in combination: a plurality of coking chambers alternating with heating walls contiguous to such coking chambers and respectively constituted of a plurality of combustion flues; the heating flues in the heating walls on two opposite sides of each of a plurality of coking chambers being communicably connected with each other; a plurality of pairs of regenerators side by side in a row; a pair of regenerators communicably connected with the flues of each heating wall, one regenerator of each pair being adapted to operate for air and the other for gas when operating for in-flow and both of each pair of regenerators being adapted to exhausting waste gases when operating for out-flow; a flow box for each regenerator, each of said flow boxes having an air valve and a waste gas valve; means to convey fuel gas optionally communicable with one flow box of each pair or directly with the heating walls with which said pairs communicate; a gas valve in said means to convey fuel gas; two rotatably mounted shafts individual to each coking chamber, that has heating flues on its two opposite sides communicably connected with each other for reversing the flow through said flues; one of said shafts operating the gas valve and air valves for the flow boxes of the pair of regenerators for the heating wall on one side of said coking chamber and the waste gas valves of the flow boxes of the pair of regenerators for the heating wall on the other side of said coking chamber, the other shaft operating the gas valve and air valve for the flow boxes of the pair of regenerators for the heating wall on said other side and the waste gas 125

valves of the flow boxes of regenerators for the heating wall on said one side; two progressively movable mechanisms operating in timed relation for actuating engagers mounted on said shafts, an engager mounted loosely on each of said shafts in the path of one of said progressively movable mechanisms, an engager fixedly mounted on each of said shafts in the path of the other progressively movable mechanism, each of said loosely mounted engagers being operatively connected with the other shaft.

3. In a coking retort oven battery having retorts and means for heating the same externally by gas burning combustion flues exterior thereto and adapted to be subjected to periodic heatings of different intensities, in combination; a pair of regenerators communicating with combustion flues of the battery; an air valve for each one of said pair; a waste gas valve for each one of said pair; a gas supply valve for each one of said pair; a pair of valve reversing devices; means operatively connecting each one of the reversing devices with the air valve and gas valve of one of the regenerators and with waste gas valve of the other regenerator; a first engager means operatively connected with the second reversing device to actuate said second reversing device of the pair; and a second engager means for the first of said reversing devices and operatively connected with said first reversing devices; two progressively movable mechanisms operable in timed relationship, one of said mechanisms being adapted for operating said reversing mechanisms and the other being adapted for operating the first and second engager means.

4. In a coking retort oven, battery, in combination: combustion chambers adapted to operate in alternation for inflow combustion and outflow of combustion products regenerators communicably connected with said combustion chambers and disposed in pairs for in-flow and out-flow; an air valve for each regenerator; a gas valve for each regenerator; a waste gas valve for each regenerator; a pair of valve reversing devices for each pair of regenerators; means operatively connecting each reversing device with its respective air valve and gas valve of one regenerator and with the waste gas valve of the other regenerator of the pair; a first engager means operatively connected to said second reversing device; a second engager means operatively connected to said first reversing device; two progressively movable mechanisms operable in timed relationship, one of said mechanisms being adapted for operating said reversing devices and the other being adapted for operating the first and second engager means; said progressively movable mechanisms being adapted for operating their respective engager means and reversing devices periodically in succession.

5. In a coking retort oven battery, in combination: coking chambers; heating walls contiguous to said coking chambers and respectively constituted of combustion flues; regenerators located at a lower level than the coking chambers and the heating walls, the regenerators being connected by ducts with the flues of said heating walls; said regenerators and heating walls being disposed in pairs for simultaneous in-flow and out-flow; an air valve, a gas valve and a waste gas valve individual to each regenerator and heating wall of a pair; a reversing device for each regenerator and heating wall of a pair; means connecting each reversing device with the air valve and gas valve of its regenerator and heating wall of the pair and with the waste gas valve of the other regenerator and heating wall of the pair; and timed means for effecting timed operation of a succession of mechanisms in succession adapted for actuating said reversing devices successively so as to reverse the flow through each pair of regenerators and heating walls in succession and timing means for effecting timed operation of said timed means.

6. In a coking retort oven battery, in combination: coking chambers; heating walls contiguous to said coking chambers and respectively constituted of combustion flues; regenerators located at a lower level than the coking chambers and the heating walls; the regenerators being connected by ducts with the flues of said heating walls; said regenerators and heating walls being disposed in pairs for simultaneous in-flow and out-flow; an air valve, a gas valve and a waste gas valve individual to each regenerator and heating wall of a pair; a reversing device for each regenerator and heating wall of a pair, means connecting each reversing device with the air valve and gas valve of its regenerator and heating wall of the pair and with the waste gas valve of the other regenerator and heating wall of the pair; and means mounted for progressive movement in circuit past the reversing devices for operating said reversing devices to reverse the flow through each pair of regenerators and heating walls of the pair.

7. In a coking retort oven battery, in combination: coking chambers; heating walls contiguous to said coking chambers and respectively constituted of combustion flues; regenerators located at a lower level than the coking chambers and the heating walls, the regenerators being connected by ducts with the flues of said heating walls; said regenerators and heating walls being disposed in pairs for simultaneous in-flow and out-flow; an air valve, a gas valve and a waste gas valve for each regenerator and heating wall of a pair; a first and a second valve reversing device for each pair of regenerators and heating walls; means connecting each one of the reversing devices with the air

valve and gas valve of one of the regenerators and heating walls of the pair and with the waste gas valve of the other regenerator and heating wall of the pair; a first engager means operatively connected with each second reversing device of a pair and a second engager means operatively connected with each first reversing device of a pair and timed means for effecting timed actuation of a series of mechanisms one after another adapted for actuating only the reversing devices one after the other and other timed means for effecting timed actuation of only the first and second engager means one after the other and timing means for effecting timed operation of said timed means.

8. In a coking retort oven battery, in combination: coking chambers; heating walls contiguous to said coking chambers and respectively constituted of combustion flues; regenerators located at a lower level than the coking chambers and the heating walls, the regenerators being connected by ducts with the flues of said heating walls; said regenerators and heating walls being disposed in pairs for simultaneous in-flow and out-flow; an air valve, a gas valve and a waste gas valve for each regenerator and heating wall of a pair; a first and a second valve reversing device for each pair of regenerators and heating walls; means connecting each one of the reversing devices with the air valve and gas valve of one of the regenerators and heating walls of the pair and with the waste gas valve of the other regenerator and heating wall of the pair; a first engager means operatively connected with each second reversing device of a pair and a second engager means operatively connected with each first reversing device of a pair and progressively movable means for actuating only the reversing devices one after the other and other progressively movable means for actuating only the first and second engager means one after the other.

9. In a coking retort oven battery, in combination: a plurality of coking chambers; heating walls contiguous to such coking chambers and constituted of combustion flues; a plurality of flow duct means respectively communicably connecting a plurality of said combustion flues with each other for simultaneous inflow and outflow; a plurality of groups of regenerators, each group comprising regenerators arranged for simultaneous inflow and outflow and in communication with a plurality of said combustion flues that are in communication with each other for simultaneous inflow and outflow; means for admitting gas to said flues; means for admitting air to the regenerators; means for discharge of waste gas from the regenerators; flow reversing means for each of said groups of regenerators; power transmitting means for transmitting power for actuating

mechanisms in succession arranged common to all of said flow reversing means and adapted to operate said flow reversing means in succession so as to periodically reverse the flow through said plurality of groups of regenerators successively.

10. In a coking retort oven battery, in combination: a plurality of coking chambers; heating walls contiguous to such coking chambers and constituted of combustion flues; a plurality of groups of regenerators communicably connected with said combustion flues, each group comprising regenerators for simultaneous inflow and outflow; means for admitting gas to said flues; means for admitting air to the regenerators; means for discharge of waste gas from the regenerators; flow reversing means for each of said groups of regenerators; power transmitting means for transmitting power for actuating mechanisms in succession arranged common to all of said flow reversing means and adapted to operate said flow reversing means in succession so as to periodically reverse the flow through said plurality of groups of regenerators successively.

11. In a coking retort oven battery, in combination: a plurality of coking chambers; heating walls contiguous to such coking chambers and constituted of combustion flues; a plurality of flow duct means communicably connecting a plurality of said combustion flues with each other for simultaneous inflow and outflow; a plurality of groups of regenerators, each group comprising regenerators arranged for simultaneous inflow and outflow and in communication with a plurality of said combustion flues that are in communication with each other for simultaneous inflow and outflow; means for admitting gas to said flues; means for admitting air to the regenerators; means for discharge of waste gas from the regenerators; flow reversing means for each of said groups of regenerators; power transmitting means for transmitting power for actuating mechanisms in succession arranged common to all of said flow reversing means and adapted to operate said flow reversing means individually and in succession so as to periodically reverse the flow through said plurality of groups of regenerators one at a time progressively.

12. In a coking retort oven battery, in combination: a plurality of coking chambers; heating walls contiguous to such coking chambers and constituted of combustion flues; a plurality of groups of regenerators communicably connected with said combustion flues, each group comprising regenerators arranged for flow simultaneously in the same direction; means for admitting gas to said flues; means for admitting air to the regenerators; means for discharge of waste gas from the regenerators; flow reversing means for each of said groups of regenerators; power transmitting means for transmitting power for actuating

tors; sequence controlling means for actuating mechanisms in succession arranged for progressive movement in circuit past all of said flow reversing means and adapted to operate said flow reversing means individually and in succession so as to periodically reverse the flow through said plurality of groups of regenerators one at a time progressively.

13. In a battery of coking retort ovens, in combination: a plurality of coking chambers; heating walls contiguous to such coking chambers and constituted of combustion flues; a plurality of flow duct means communicably connecting a plurality of said combustion flues with each other for simultaneous inflow and outflow; a plurality of groups of regenerators, each group comprising regenerators arranged for simultaneous inflow and outflow and in communication with a plurality of said combustion flues that are in communication with each other for simultaneous inflow and outflow; means for admitting gas to said flues; means for admitting air to the regenerators; means for discharge of waste gas from the regenerators; flow reversing means for each of said groups of regenerators; sequence controlling means for actuating mechanisms in succession by progressive movement in circuit past mechanisms to be actuated thereby mounted for progressive movement in circuit past all of said flow reversing means and adapted to operate said flow reversing means in succession so as to periodically reverse the flow through the groups of regenerators for said battery of ovens successively.

14. In a battery of coking retort ovens, in combination: a plurality of coking chambers; heating walls contiguous to such coking chambers and constituted of combustion flues; a plurality of groups of regenerators communicably connected with said combustion flues, each group comprising regenerators arranged for simultaneous inflow and outflow; means for admitting gas to said flues; means for admitting air to the regenerators; means for discharge of waste gas from the regenerators; flow reversing means for each of said groups of regenerators; sequence controlling means for actuating mechanisms in succession by progressive movement in circuit past mechanisms to be actuated thereby mounted for progressive movement in circuit past all of said flow reversing means and adapted to operate said flow reversing means in succession so as to periodically reverse the flow through the groups of regenerators for said battery of ovens successively.

15. In a coking retort oven battery having retort chambers adapted to be respectively externally heated by gas burning combustion flues adapted to be subjected to periodic heatings of different intensities and having re-

generators in communication with said flues and having reversing valves for reversing the flow of gas and air for combustion in said flues, in combination: a reversal mechanism comprising a pair of rotatable members each adapted for effecting an opening and a closing movement of certain of said reversing valves when rotated; an engager fixed on each member to rotate the same for effecting one of said movements by said member; an engager loosely mounted on each member, the engagers loosely mounted on the members being operatively connected with the other member of the pair to move the other members for effecting the other of said movements by said members when said loosely mounted engagers are engaged.

16. In a coking retort oven battery having retort chambers adapted to be respectively externally heated by gas burning combustion flues adapted to be subjected to periodic heatings of different intensities and having regenerators in communication with said flues and having reversing valves for reversing the flow of gas and air for combustion in said flues, in combination: a reversal mechanism comprising a pair of oppositely disposed rotatable members each adapted for effecting an opening and a closing movement of certain of said reversing valves when rotated; an engager fixed on each of the members to rotate the same for effecting one of said movements by said member; an engager loosely mounted on each of said members, each loosely mounted engager being connected with the opposite rotatable member of the pair for rotating the member for effecting the other of said movements by the member; a plurality of progressively movable mechanisms, one of said mechanisms engaging said loosely mounted engagers to rotate the oppositely disposed rotatable member of the pair, and the other of said mechanisms engaging the fixed engagers to rotate the members to which said fixed engagers are fixed.

17. In a coking retort oven battery, in combination: a series of alternate substantially parallel retort chambers and heating walls therefor arranged side by side, each of said heating walls comprising combustion flues operable in alternation for inflow combustion and outflow of combustion products; a plurality of groups of regenerators communicably connected with said combustion flues, each group comprising regenerators arranged for simultaneous inflow and outflow; means to convey fuel gas to said flues; an air supply for the regenerators; waste gas outlets for the regenerators; periodically operable flow reversing devices for the regenerators and flues; and power transmitting means for transmitting power for actuating mechanisms one after another adapted for operating said reversing devices one after another.

18. In a coking retort oven battery, in

- combination: a series of alternate substantially parallel retort chambers and heating walls therefor arranged side by side, each of said heating walls comprising combustion flues operable in alternation for inflow combustion and outflow of combustion products; a plurality of groups of regenerators communicably connected with said combustion flues, each group comprising regenerators arranged for simultaneous inflow and outflow; means to convey fuel gas to said flues; an air supply for the regenerators; waste gas outlets for the regenerators; periodically operable flow reversing devices for the regenerators and flues; and progressively movable means for actuating mechanisms one after another by progressive movement relative thereto adapted for operating said reversing devices one after the other.
19. In a coking retort oven battery, in combination: a series of alternate substantially parallel retort chambers and heating walls therefor arranged side by side, each of said heating walls comprising combustion flues adapted to be subjected to periodic heatings of different intensities; a plurality of groups of regenerators communicably connected with said combustion flues, each group comprising regenerators arranged for simultaneous inflow and outflow; means to convey fuel gas to said flues; an air supply for the regenerators; waste gas outlets for the regenerators; periodically operable flow reversing devices for the regenerators and flues; and power transmitting means for transmitting power for actuating devices in succession adapted for operating said reversing devices in succession.
20. In a coking retort oven battery, in combination: a series of alternate substantially parallel retort chambers and heating walls therefor arranged side by side, each of said heating walls comprising combustion flues operable reversely in alternation for inflow combustion and outflow of combustion products; a plurality of groups of regenerators communicably connected with said combustion flues, each group comprising regenerators arranged for simultaneous inflow and outflow; means to convey fuel gas to said flues; an air supply for the regenerators; waste gas outlets for the regenerators; periodically operable flow reversing devices for the regenerators and flues; and progressively movable means for actuating mechanisms in succession by progressive movement relative thereto adapted for operating said reversing devices in succession.
21. In a coking retort oven battery, in combination: a battery of coking chambers and combustion flues therefor, and a battery of regenerators communicably connected with said combustion flues; means for admitting gas to said flues, means for admitting air to the regenerators; means for discharge of waste gas from the regenerators; flow reversing means for each of said regenerators; and power transmitting means for transmitting power for actuating mechanisms in sequence arranged common to all of said flow reversing means and adapted to operate said flow reversing means in sequence to periodically reverse the flow through the regenerators sequentially.
22. In a coking retort oven battery, in combination: a battery of coking chambers and combustion flues therefor, and a battery of regenerators communicably connected with said combustion flues, said regenerators being communicably connected with the flues in groups comprising regenerators adapted for gas flow simultaneously in the same direction; means for admitting gas to said flue; means for admitting air to the regenerators; means for discharge of waste gas from the regenerators; flow reversing means for each of said groups of regenerators; and power transmitting means for transmitting power for actuating mechanisms in sequence arranged common to all of said flow reversing means and adapted to operate said flow reversing means in sequence to periodically reverse the flow through the groups of regenerators sequentially.
- In testimony whereof I have hereunto set my hand.
- JOSEPH VAN ACKEREN.
